UNITED STATES PATENT OFFICE.

AUGUST F. HABENIGHT, OF TINLEY PARK, ILLINOIS.

CONTROLLING APPARATUS FOR AIR-PRESSURE SYSTEMS FOR PUMPS.

Application filed July 5, 1924. Serial No. 724,392.

To all whom it may concern:

Be it known that I, AUGUST F. HABENIGHT, a citizen of the United States, residing at Tinley Park, in the county of Cook

5 and State of Illinois, have invented certain new and useful Improvements in Controlling Apparatus for Air-Pressure Systems for Pumps, of which the following is a specification.

10 This invention is quite similar to that disclosed in my co-pending application Serial No. 620,820, filed February 23, 1923, for a like apparatus, and embodies improvements over the structure set forth in said application, as well as improvements in air pumping

15 apparatus generally.

My present application, like the above mentioned co-pending application, while being more particularly intended for use in pumping water from earth wells and cisterns, yet is applicable for use in pumping water or liquids from various kinds of containers whether located above ground or below the same, and has for its principal object to provide a pneumatically operated pumping apparatus which shall be automatic and efficient in its operation, simple and inexpensive in construction and installation, strong, durable, and with its parts so

20 constructed and arranged as to be easily accessible for changes and repairs.

Another object of my present invention is to improve, simplify, render more efficient, and avoid certain difficulties heretofore encountered in the means or connections for controlling the flow of compressed air from a reservoir therefor to, from, and through certain parts of the apparatus.

Other objects and advantages of the invention will be disclosed in the following description and explanation.

The invention consists in certain peculiarities of the construction, novel arrangement and combination of the various parts there- 45 of as will be hereinafter more fully described and explained, which explanation will be more readily understood when read in conjunction with the accompanying drawings, in which an embodiment of which the invention is susceptible, is disclosed, it being obvious that changes and modifications may be resorted to without departing from the spirit of the appended claims forming a part hereof.

50 In the drawings, Fig. 1 is a general or dia- grammatic view of the apparatus, showing

it installed in connection with an earth well, with its parts in their operative positions, for forcing or pumping the water from the well.

60 Fig. 2 is an enlarged view partly in section and partly in elevation taken on line 2—2 of Fig. 3 looking in the direction indicated by the arrows, showing certain parts of the apparatus mounted on a suitable support therefor and in the positions illustrated in Fig. 1.

Fig. 3 is a view of like parts in similar positions looking in the direction of the pressure controlling cylinder mounted on 70 the said support but with the support interposed.

Fig. 4 is a similar view to Fig. 2 showing about the positions the parts will occupy when air pressure is shut off from the source 75 of supply, and is being exhausted from the air tank located within the well.

Fig. 5 is a greatly enlarged sectional view 80 of a diaphragm and its casing used in connection with the apparatus.

Fig. 6 is an enlarged view in side elevation of parts of the connections leading from the master valve of the apparatus to the pressure controlling cylinder and their valves 85 for controlling the flow of compressed fluid between said valve and cylinder, and

Fig. 7 is an enlarged plan sectional view taken on line 7—7 of Fig. 6.

Like numerals of reference refer to corresponding parts throughout the different 90 views of the drawings.

Referring now more particularly to Fig. 1 of the drawings, the reference numeral 10 designates a water or liquid container such as a well, in which is suspended so as 95 preferably to be entirely submerged in the water 11 of said container, a tank 12 which is hermetically sealed except at its bottom or lower portion, in which is provided a port or opening 13 having around the same 100 on the upper surface of said bottom, or on the inner surface of the tank 12, a valve seat 14 to co-act with a gravity valve 15 for the purpose of admitting water to said tank.

105 Located near the well or container, or at any suitable distance therefrom, is a large reservoir 18 for holding the compressed air, which may be supplied thereto by any suitable means and in sufficient quantity for use for a considerable length of time. Leading 110 from this reservoir is a pipe 19 which is equipped with a pressure reducing valve 20

of the ordinary or any well known construction and communicates with a valve casing 21 which forms part of a larger or master valve casing 22 which latter casing may be 5 mounted on a suitable support 23 located near or remote from the well or liquid container 10 and supported in any suitable manner. The valve casing 21 has a port 16 leading to the casing 22, which port is surrounded by an upwardly extended valve seat 24 for co-operation with a valve 25 the stem 26 of which is mounted on a bar 27 hinged or loosely and adjustably connected at one of its ends for vertical movement, for instance, to a screw 17 or other suitable projection depending from the upper surface of the valve casing 22 near one end thereof.

The valve casing 22 is provided preferably on its upper surface near its end opposite 20 the member 17 with an exhaust valve casing 28 which is provided with one or more ports 29 and has vertically and slidably mounted therein a valve stem 30 which carries on its lower end a valve 31 to close the valve seat 25 32 of the casing 28.

Depending from the valve 31 is an extension 33 which is reduced towards its lower end and provided on said end with a head or enlargement 34. The bar 27 which 30 co-operates with the valve stem 26 is provided with an elongated slot 35 at its free end for loose engagement with the reduced portion of the extension 33 of the exhaust valve. The upper end of the valve stem 35 30 is provided with a head 36 having thereon a horizontally extended arm 37 for the purpose to be presently explained. Fulcrumed on the lower portion of the support 23 is a lever 38 which is adapted to operate 40 in a slot 39 in said support and to co-operate at one of its ends with the head 36 of the valve stem 30 for closing the valve 31 under certain conditions.

Leading from the valve casing 22 is a 45 pipe 41 which is extended through the cover 42 of the well or water container 10 and communicates at its lower end with the upper end of the tank 12 to which end of said tank it may be secured in such a manner as to assist in supporting the same. This last mentioned pipe is employed for conveying pressure from the master valve casing 22 to the tank 12 and may be fixed to the cover 42 of the water container in any 50 suitable manner so as to assist in supporting the said tank. The upper portion of the support 23 has journaled thereon a pulley 44 over which is extended a cable 45 which is connected at one of its ends to the upper 55 end of a longitudinally bored weight 46 which has the lower end of its bore contracted as at 48 in Fig. 2 of the drawings.

Slidably located in the bore or cavity of the weight 46 is a rod 47 which has on its 60 upper end a cone-shaped head 48 to restrict

the movement of said rod in a downward direction. The rod 47 extends into a vertically disposed guide 48^a mounted on a bracket 49 with which the support 23 is provided at a suitable distance above its 70 lower end.

Rigidly mounted on the lower end of the rod 47 is a weight 50 which is adapted for vertical movement in the guide 48^a. The other end of the cable 45 has secured thereto at about its middle a cross-piece 54 from which depend a pair of connections 55 which are connected at their lower ends to a cross-piece 56 in such a way that the connections 55 will stride the controlling cylinder 57 80 which is vertically mounted on the support 23 at a suitable point thereon; the cross-pieces 54 and 56 are disposed in parallelism with one another in such a way that their path of travel will diametrically intersect 85 the cylinder 57 in the operation of the apparatus.

Extended from the upper end of the cylinder 57 is an elbow pipe 51 which has connected thereto a T-coupling 52 provided with a removable plug 53 in its stem, which can be removed to permit lubricant to be supplied to the interior of the cylinder for lubricating the piston head thereof. Connected to the outer end of the coupling 52 is one end of another T-coupling designated as a whole by the numeral 52^a the stem 53^a of which constitutes the casing for a needle valve 54^a seated in the member 53^a so as to open and close a port in said member leading into a channeled valve casing 55^a which is horizontally extended from the member 53^a above the coupling 52 as is clearly shown in Figs. 2 and 6 of the drawings. This valve casing 55^a is provided with an outlet port 56^a near its free end and about midway between its ends on one side thereof with a screw-threaded stem 57^a disposed at a right angle to the casing 55^a as shown in Fig. 7 of the drawings.

Pivots mounted on the stem 57^a is a valve bar 58 which is pressed against the adjacent side of the casing 55^a by means of a spring 59 coiled around the stem 57^a and resting at one of its ends against the member 58 and at its other end against a nut 60 on the stem 57^a used for regulating the tension of said spring. Pivots connected at its upper end to that end of the valve bar 58 adjacent the cylinder 57 is a rod 61 the lower end of which is adjustably secured to the arm 37 carried by the stem 30 of the exhaust valve of the master valve casing 22 as will be readily understood by reference to Figs. 2 and 4 of the drawings.

Fitted in the outer end of the T-coupling 52^a is another T-shaped coupling or valve casing 62 which has connected to the stem thereof the upper end of a pipe 63 the lower end of which is connected preferably by

means of a coupling 64 with the master valve casing 22 usually on top thereof. Adjustably fitted in the end of the valve casing or T-coupling 52^a remote from the cylinder 57 is a needle valve 65 employed for regulating the flow of compressed air from the casing 22 into the controlling cylinder.

By the arrangement of the parts 51 to 64 inclusive, and in addition by the employment of the pipes 19 and 41 communicating with the master valve casing 22, it is apparent that a connection communicably uniting the tank 12, the reservoir 18 and the pressure controlling cylinder 57 is provided by means of which not only the flow of compressed air from the master valve casing 22 into the controlling cylinder can be regulated, but also that the exhaust from said cylinder can be positively controlled in such a way as to prevent accumulation of condensation in the pipe 63 leading from the master valve to the valve casing 62 as frequently occurred, and was found objectionable in the pipe for a corresponding purpose of my aforesaid application. Furthermore, by my present improvements, a valve controlled exhaust or vent casing for the pressure controlling cylinder 57 of such a character as to prevent at all times leakage on account of the wear of certain parts of an arrangement or construction for the same purpose employed in my aforesaid pending application, is provided by the use of the spring-pressed sliding valve bar 58 and its parts co-operating with the exhaust valve of the master valve casing of the apparatus.

Extended through the cover 42 of the well or water container 10 is a service pipe 65^a which may be equipped with a branch pipe 66 and a faucet 67 for drawing water from the tank 12, into which the pipe 65 is extended to a point near the bottom of said tank. This pipe 65^a is also connected to the cover 42 and the top of the tank 12 so as to assist in supporting said tank.

By reference to Figs. 1, 2 and 4 of the drawings it will be seen and understood that the lever 38 is so located and supported on the support 23 that one of its ends will be located in the path of the travel of the weight 50, while its other end is located in the path of travel of the head 36 on the stem of the exhaust valve of the master casing. It will also be observed that the lever 38 has the upper portion of its ends rounded to form bearing surfaces for co-action with the lower surfaces of said head and weight. By thus locating the lever 38, it is evident that upon the downward movement of the weight 50 the same will strike the rounded portion of one end of said lever and cause the same to be depressed as shown in Fig. 2 of the drawings, when the compressed fluid shall have been exhausted from the controlling cylinder. In this movement

of the parts it is manifest that the exhaust valve in communication with the valve casing 22 will be closed and that at the same time the inlet or supply valve 25 for compressed air will be opened and remain in such position as long as the weight 50 remains in contact with the lever 38, and that when the parts are thus positioned as just above mentioned, the sliding valve bar 58 will be closed.

Mounted on a suitable bracket 66 extended from the upper portion of the guide 48^a is a diaphragm casing which comprises a pair of convex disks or members 67 and 68 which have their concave surfaces facing each other and are secured together in any suitable manner. Located between the members 67 and 68 is a diaphragm 69 of rubber or any other suitable material which is held by the members of the diaphragm casing near its edges. Extended through a suitable opening in the member 68 is a slidable rod 70 which by preference has on its end adjacent the diaphragm an enlargement 71 to rest against said diaphragm. The opposite end of the rod 70 rests against an arm or plate 72 which is pivoted to the bracket 66 and extends downwardly therefrom and has at its lower portion a laterally extended arm 73 provided with a projection 74 extended downwardly or laterally from said last named arm.

The member 72 is provided in its portion below the arm 73 with a transverse opening in which is slidably located a trip rod 75 which also extends through an opening in the extension 74 and has its end adjacent said extension screw-threaded for engagement with a nut or nuts 76 used for regulating the tension of a spring 77 surrounding the trip rod 75 between the extension 74 and the member 72 below the arm 73 thereon. One end of the spring 77 rests against the extension 74 while the other end of said spring rests against an enlargement 78 carried by the rod 75, by which arrangement it is manifest that the rod 75 can be advanced or retracted as desired and the tension of the spring 77 actuating said rod regulated. Fixed at one of its ends to the lower portion of the member 72 is a rod 79 which is movably extended through a suitable opening in the lower portion of the diaphragm casing as is clearly shown in Figs. 4 and 5 of the drawings. Surrounding the rod 79 and resting at one of its ends against the diaphragm casing on that surface thereof opposite the member 72 is a spring 80 the other end of which spring rests against the washer 81 which is mounted on the rod 79 near its outer end, which washer is held in constant contact with the spring 80 by means of an adjusting nut 82 threaded on the outer end of the rod 79 and employed for the purpose of regulating the

tension of the spring 80 thereby affording means for regulating the degree of pressure required within the diaphragm casing for operating the trip members 72 and 75, the functions of which will be presently explained.

Extending from the diaphragm casing or member 67 and communicating with its cavity is one end of a pipe 83 the other end of which communicates with an expansion casing or chamber 84 which has communication with the upper portion of the service pipe 65 and may be supported in any suitable or well known way. The service pipe 65 is provided with a check valve 85 which is by preference located externally of the water container. Fulcrumed on that side of the guide 48^a adjacent the support 23 is a gravity actuated bell crank lever 86 the longer arm of which is provided with an adjustable weight 87 and extended alongside the piston rod 88 above the cross-piece 56 and between the connections 55 which unite the cross-piece 56 to the other cross-piece 54 or upper one. The shorter arm 89 of the lever 86 is provided with a hook 90 which is adapted when the lever is moved by its gravity, to the position shown in Fig. 4 of the drawings, to pass through an opening 91 in the guide 48^a and engage the bottom or lower end of the weight 50 adjacent said lever so as to hold the weight in its raised position. Diametrically opposite the opening 91 in the guide 48^a another opening 92 is provided therein and is for the operation of the trip pin or rod 75 operated by the pressure in the diaphragm under certain conditions and adapted to engage the lower end of the weight 50 as shown in Fig. 4 of the drawings. The longer arm of the lever 86 is extended through a vertical slot 93 in the support 23 just below the lower end of the controlling cylinder 57, so that said longer arm will be in the path of the cross-piece 56, and close to the piston rod 88, which rod has mounted thereon within the cylinder 57 a piston head 94 for reciprocation in said cylinder. This piston head can be lubricated by the passage of a suitable lubricant into the cylinder by removing the plug 53 from the T-coupling 52 and then placing a quantity of lubricant in said coupling from which it will pass into the cylinder.

From the foregoing and by reference to the drawings, it will be readily understood and clearly seen, assuming the parts to be in the positions shown in Figs. 1 to 3 inclusive of the drawings, and that the needle valve 65 which controls the quantity or flow of compressed fluid from the master valve casing 22 through the pipe 63 to the valve casing or coupling 62 in which said needle valve is located, is adjusted so as to permit enough air pressure to be supplied to the

controlling cylinder 57 to cause the piston head 94 to be forced from the top of the cylinder to about the position shown in Fig. 4 substantially during the time it takes for the water to be discharged or drawn off from the tank 12, compressed air from the reservoir 18 will pass through the pipe 19 and pressure reducing valve 20, which valve may be so adjusted as to permit a predetermined pressure of air to pass through the pipe 19 to the coupling 64 and from thence through the valve casing 22 and pipe 41 to the tank or receptacle 12 located as above stated within the well or water container so as to be partly sunk in the water or if desired, completely submerged therein.

As the tank 12 is only partially filled with water, it is apparent that the space therein above the water will be filled with air, the degree of pressure of which will be regulated by the reducing valve 20 as above mentioned. This pressure within the tank 12 against the water in said tank is considerably greater than the atmospheric pressure on the main body of water in the well and consequently will force the water through the pipe 65^a so as to be drawn off through the faucet 37 when the latter is opened.

By the use of the needle valve 65, which as before stated controls the flow of compressed air from the valve casing 22 to the upper end of the controlling cylinder 57, it is manifest that as said valve is constantly open, pressure equal to that in the water receptacle 12 and the valve casing 22 will be supplied to the controlling cylinder against the piston head thereof, so as to cause said head and its rod to be moved downwardly, it being understood that the degree of said pressure being greater than the gravity of the weights 46 and 50, will cause said weights to be elevated from the positions shown in Figs. 1 to 3 inclusive until they reach about the positions shown in Fig. 4 of the drawings. In this operation, the upper end of the weight being downwardly enlarged will, should the trip pin or rod 75 and the hook 90 of the lever 86 be extended through the openings 92 and 91 therefor respectively be caused to move outwardly of said openings so as not to materially retard the downward movement of the said weights, especially the weight 50 or lower one. Furthermore, by employing the spring 77 on the rod 75, it is manifest that the movement of said rod can be regulated to a very sensitive degree so that should the inner end of said rod at any time press against the side wall of the weight 50, such pressure would not be sufficient to interfere with the downward movement of the weight.

When the parts are in the positions shown in Fig. 4, it is obvious that the sliding bar valve 58 will be moved so as to open the port 56^a of the valve casing 55^a thus per-

mitting the exhaust of air from the cylinder 57 through the elbow pipe 51, couplings 52 and 53^a, as well as the casing 55^a, and that thus pressure in the cylinder 57 will be reduced to such an extent as to permit the weight 46 to descend independently of the rod 47 and weight 50, at which time the cross-piece 56 carried by the piston rod 88 will strike the lever 86 thus causing the hook 10 90 to be disengaged from the weight 50. This last named weight will now be held by the trip pin or rod 75 actuated by the diaphragm when the faucet 67 is open for the withdrawal of water, which will reduce 15 the pressure in the expansion chamber 84 and through the pipe 83 in the diaphragm casing to such an extent as to permit the tension exerted by the spring 80 to disengage the trip pin 75 from the weight 50, 20 when the same will automatically assume the position shown in Fig. 2 of the drawings.

By positioning the needle valve 65 in the connection or means for controlling the pressure in the cylinder 57 at near the upper end of said cylinder and by employing the vertically disposed pipe 63 leading from the said needle valve casing to the master valve casing, it is obvious that accumulation of 25 condensation in said pipe will be avoided and furthermore, that said needle valve will be located in a more accessible position. It is further apparent that by employing the sliding valve bar 58 constructed as set 30 forth for the valve casing 58^a, wear of the parts will be compensated for by the pressure of the spring 59 against said valve bar thus preventing liability of leakage of air 35 to such an extent as to affect the efficiency 40 of the apparatus.

Having thus fully described my invention, what I claim as new and desire to secure by Letters Patent is:

1. In an apparatus of the class described, 45 the combination with a supply of compressed air, of a tank having a valve controlled intake communicating with a supply of water, a connection communicably uniting said tank and said air supply, valved means 50 operating with said connection for controlling the passage of air from said tank, said controlling means including an exhaust valve in said connection, an upright cylinder, a piston for reciprocation therein, a 55 pipe communicating at its lower end with a part of said connection and at its upper end with the upper portion of said cylinder, said pipe being disposed vertically throughout its length to prevent accumulation of 60 condensation therein, and an adjustable needle valve cooperating with the upper end of said pipe to regulate the supply of air therethrough to said cylinder.

2. In an apparatus of the class described, 65 the combination with a supply of compressed

air, of a tank having a valve controlled intake communicating with a supply of water, a connection communicably uniting said tank and said air supply, valved means 70 operating with said connection for delivering compressed air to said tank, and means also cooperating with said connection for controlling the passage of air from said tank, said last named means including an exhaust valve in said connection, an upright 75 cylinder, a piston for reciprocation therein, a pipe communicating at its lower end with a part of said connection and at its upper end with the upper portion of said cylinder, said pipe being disposed vertically throughout its length to prevent accumulation of 80 condensation therein, and an adjustable needle valve cooperating with the upper end of said pipe to regulate the supply of air therethrough to said cylinder.

3. In an apparatus of the class described, the combination with a supply of compressed air, of a tank having a valve controlled intake communicating with a supply of water, a connection communicably uniting said 90 tank and said air supply, valved means operating with said connection for delivering compressed air to said tank, and means also cooperating with said connection for controlling the passage of air from said tank, said last named means including an exhaust valve in said connection, an upright cylinder, a piston for reciprocation therein, a pipe communicating at its lower end with a part of said connection and at its upper 95 end with the upper portion of said cylinder, said pipe being disposed vertically throughout its length to prevent accumulation of condensation therein, an adjustable needle valve cooperating with the upper end of said 100 pipe to regulate the supply of air therethrough to said cylinder, and a weight connected to said piston to actuate it in one direction.

4. In an apparatus of the class described, 110 the combination with a supply of compressed air, of a tank having a valve controlled intake communicating with a supply of water, a connection communicably uniting said tank and said air supply, valved means 115 operating with said connection for delivering compressed air to said tank, and means also cooperating with said connection for controlling the passage of air from said tank, said last named means including an exhaust valve in said connection, an upright cylinder, a pipe communicating at its lower end with a part of said connection and at its upper end with the upper portion of 120 said cylinder, said pipe being disposed vertically throughout its length to prevent accumulation of condensation therein, an adjustable needle valve cooperating with the upper end of said pipe to regulate the supply of air therethrough to said cylinder, and a 125

130

weight actuated piston head and rod mounted for reciprocation in said cylinder for co-operation with said exhaust valve to open the same when moved in one direction and 5 to close said valve when actuated by weight in the opposite direction.

5. In an apparatus of the class described, the combination with a supply of compressed air, of a tank having communication with a supply of water, means for controlling the flow of water into said tank, a connection communicably uniting said compressed air supply and said tank, a pipe communicating at its lower end with said 10 connection and an adjustable needle valve cooperating with the upper portion of said pipe to regulate the quantity of air discharged therethrough, said pipe being disposed vertically throughout its length to 15 prevent accumulation of condensation therein.

6. In an apparatus of the class described, the combination with a supply of compressed air, of a tank having communication 25 with a supply of water, a connection communicably uniting said tank and said air supply, valved means cooperating with said connection for delivering compressed air to said tank, a vertically mounted cylinder, valve controlled means for the passage 30 of air from said connection to the upper end of said cylinder, a piston mounted for reciprocation in the cylinder, gravity actuated means connected to said piston for 35 moving it in one direction, an exhaust outlet at the upper portion of the cylinder, said outlet including a needle valve controlled valve casing having a discharge port and a spring pressed sliding valve 40 controlling said port, and means cooperating with said sliding valve and said piston for opening the port of said valve casing upon the movement of the piston in one direction.

7. In an apparatus of the class described, 45 the combination with a supply of air under pressure, of a vertically mounted cylinder,

a connection communicably uniting the upper portion of said cylinder with said air supply, valved means in said connection for regulating the discharge of air into said cylinder and for controlling the exhaust of air therefrom, said exhaust controlling means including a needle valve controlled casing in said connection having a discharge port and a spring pressed sliding valve controlling said port, and means co-operating with said sliding valve and said piston for opening the port of said valve casing upon the movement of the piston in one direction. 60

8. In an apparatus of the class described, the combination with a supply of compressed air, of a tank having communication with a supply of water, a valved casing having communication with said supply of compressed air, an air supply pipe leading from said casing to the tank, a valved water delivery pipe leading from the tank, an expansion chamber casing in communication with said delivery pipe, a vertically mounted cylinder, a valved connection uniting the upper portion of said cylinder to said valved casing, a weight actuated piston in said cylinder, a guide for said weight, a diaphragm casing supported near said guide, 75 a diaphragm within the last named casing, a plunger actuated by said diaphragm and extended through the casing thereto, a pivoted arm in contact with said plunger and having a spring-actuated trip pin adapted to extend 80 into said guide and to cooperate with the piston actuating weight to releasably hold it, means cooperating with said arm and said pin to regulate the tension of the spring for said pin, a rod fixed at one end to said 85 arm and movably supported by the diaphragm casing, a tensioning spring on the outer portion of said rod and a pipe connecting the diaphragm casing with said chamber. 90

AUGUST F. HABENICHT.
